CLAMP FOR PANEL FORMS

Theodore A. Kus, Oak Lawn, Ill., assignor to Universal Form Clamp Co., Chicago, Ill., a corporation of Illinois

Filed Oct. 15, 1965, Ser. No. 87,511

Term of patent 14 years

(Cl. D54—1)

FIG. 1

FIG. 5

FIG. 2

FIG. 6

FIG. 3

FIG. 7

I claim:

The ornamental design for a clamp for panel forms, substantially as shown.
